UNITED STATES PATENT OFFICE.

JOHN F. PETIT, OF GEORGETOWN, ILLINOIS.

BED-WARMER.

1,082,135.

Specification of Letters Patent. Patented Dec. 23, 1913.

Application filed May 15, 1913. Serial No. 767,851.

To all whom it may concern:

Be it known that I, JOHN F. PETIT, a citizen of the United States, residing at Georgetown, in the county of Vermilion and State 5 of Illinois, have invented certain new and useful Improvements in Bed-Warmers; and I do declare the following to be a full, clear, and exact description of the invention, such as will enable others skilled in the art to 10 which it appertains to make and use the same.

This invention relates to improvements in bed warmers.

One object of the invention is to provide 15 a bed warmer adapted to be supported beneath the mattress or bottom of a bed and which will evenly distribute the heat to all parts of the bed.

Another object is to provide a bed warmer 20 adapted to receive any kind of heat or to which may be applied any suitable heat producing apparatus.

With these and other objects in view, the 25 invention consists of certain novel features of construction, and the combination and arrangement of parts as will be more fully described and claimed.

In the accompanying drawings: Figure 1 is a vertical longitudinal section of the 30 warmer. Fig. 2 is a cross sectional view thereof showing the centrally disposed transverse supporting bar in full lines. Fig. 3 is an end view of the foot end of the 35 warmer showing the arrangement of the draft opening and damper plate.

My improved bed warmer comprises a flat rectangular hollow body 1 formed of sheet metal and having its bottom, sides and ends constructed of double walls between which is 40 arranged a packing 2 of asbestos or other suitable material. The top 3 of the warmer is of single thickness and from said top the heat radiates and passes upwardly against the spring bottom or mattress of the bed 45 whereby the latter is thoroughly and uniformly heated over its entire surface.

The body 1 is substantially the same size and shape as the bottom of the bed to which the warmer is applied and the warmer is 50 secured to the bedstead and supported beneath the bottom thereof by any suitable means.

Arranged in the body of the warmer and extending from one end to a point near the 55 opposite end thereof and from one side to the other is a baffle or heat deflecting plate

8 by means of which the heat passing through the body of the warmer is directed from one end thereof to the opposite end and back as clearly indicated by arrows in 60 Fig. 1 of the drawing. The plate 8 is supported in an inclined position by transverse supporting bars 9 the ends of which are bent downwardly to form supporting lugs 10 of suitable length for supporting the baffle 65 plate at the desired inclination as clearly shown in Figs. 1 and 2 of the drawing. Arranged on the plate 8 at the lower or foot end of the warmer is a sheet of asbestos 8^a the purpose of which will be hereinafter described. 70

The construction and arrangement of the flat heat deflecting plate 8 constitutes the most essential feature of the invention for the reason that the heat is gradually expanded until it reaches the free elevated end of said plate, the heat at this point being contacted by the end member of the hollow body and the contracted entrances of the upper passage after which the heat is again 80 expanded along the entire upper surface or wall of said body. 75

By contracting the heat and gradually expanding the same in the manner described, the hollow body 1 is retained at an even 85 temperature throughout its entire structure.

In the lower side of the foot end of the warmer and in one corner of said end is arranged a heat receiving opening 11 which is surrounded by a depending flange 12 projecting a suitable distance below the bottom of the warmer as shown. Any suitable heat producing apparatus may be applied to the flanged opening 11 for supplying the heat for the warmer, which is adapted to project 90 into the space surrounded by the depending flange 12 as clearly shown in Fig. 1 of the drawing. The front side of the flange 12 is hinged at its upper edge to form a door 12^a which may be swung upwardly to permit a 100 lamp to be placed beneath the opening 11, without being tilted.

In the foot end of the warmer at the opposite corner from the opening 11 is a draft opening 13 along the side edges of which 105 are arranged guide flanges 14 with which is slidably engaged the edges of a damper plate 15. The plate 15 is adjusted between said cleats and over the opening 13 to regulate the size thereof, by means of an operating rod 16 which extends through guides on the end of the warmer to the opposite side 110

thereof and near the hinged side of the flange 12, whereby the damper plate may be readily adjusted from the side of the bed. By adjusting the damper plate 15 it will be seen that the passage of the heat through the warmer may be regulated and the temperature of the bed thus controlled.

From the foregoing description taken in connection with the accompanying drawings, the construction and operation of the invention will be readily understood without requiring a more extended explanation.

Various changes in the form, proportion and the minor details of construction may 15 be resorted to without departing from the principle or sacrificing any of the advantages of the invention as claimed.

Having thus described my invention, what I claim is:

20 A bed warmer comprising a hollow body

having a heat supply opening, a flat deflecting plate gradually inclined from the heat supply opening of the body and terminating adjacent to the opposite end wall of said body, forming a gradually expanding 25 passage beneath the deflecting plate from the heat supply opening to the opposite end wall, and a gradually expanding passage above said deflecting plate from said opposite end wall to the heat supply end of the warmer, 30 and means for supplying heat thereto, and means for regulating the latter.

In testimony whereof I have hereunto set my hand in presence of two subscribing witnesses.

JOHN F. PETIT.
